UNITED STATES PATENT OFFICE

2,070,721

CATAPULT

Charles Donald Feight, Glassport, Pa.

Application August 14, 1936, Serial No. 96,109

5 Claims. (Cl. 244—63)

This invention appertains to new and useful improvements in catapults and more particularly to a novel apparatus for projecting aerial toys such as toy aeroplanes.

5 The principal object of the present invention is to provide an apparatus which is used to simulate the catapulting of aeroplanes in a manner which will have a marked resemblance to the take-off of aeroplanes from an aviation field.

10 Another important object of the invention is to provide an apparatus of the character stated which will be substantially fool-proof in operation and not susceptible to the development of undeterminable defects.

15 These and various other important objects of the invention will become apparent to the reader of the following specification.

In the drawings:—

Figure 1 represents a top plan view of the apparatus.

20 Figure 2 represents a front elevational view of the structure.

Figure 3 is a horizontal sectional view through the apparatus.

25 Figure 4 is a longitudinal sectional view.

Figure 5 is a fragmentary detailed sectional view taken substantially on the line 5—5 of Figure 3.

30 Figure 6 is a fragmentary longitudinal sectional view through the trip means of the apparatus.

Figure 7 is a fragmentary vertical sectional view on the line 7—7 of Figure 4.

35 Figure 8 is a fragmentary elevational view of the vertical pulley-gear shown in Figure 3.

Referring to the drawings wherein like numerals designate like parts, it can be seen that numeral 5 represents the base of the apparatus which is provided with upstanding end walls 6—6

40 and side walls 7. The numeral 8 represents a house-like structure mounted upon one end of the aforementioned structure and simulating an aeroplane hangar. Numeral 9 represents the top of the structure which corresponds to the take-

45 off field and which has an opening 10 therein within the housing 8 above which the turntable 11 is located. This turntable 11 is carried by the shaft 12 on which is located the bevel gear 13 with which the bevel gear 14 on the shaft 15

50 meshes. This shaft 15 is journaled through one side wall 7 and is equipped with a crank handle 16. Between the side walls 7—7, a shaft 17 is journaled and has a pulley 18 thereon corresponding to the pulley 19 on the gear 14 and

55 a belt 20 is trained over the pulleys so that by

rotating the shaft 15 the turntable 11 will be rotated as well as the shaft 17. Bearing structures 21—21 depending from the platform 9 support the idler shaft 22 with the pulley 23 thereon. As is shown in Figure 3 the shaft 17 also has the pulley 24 and over these pulleys 23—24 is trained the elongated endless belt 25.

Overlying the belt 25, the platform 9 is provided with a longitudinal extending slot 26 through which the pins 27 on the forward end 10 of the toy aeroplane 28 depends.

Guide plates 29—29 are provided at the sides of the belt 25 and extend above and below the flights of the belt as well as beyond the pulleys 23—24. These guide plates 29 serve as rails for 15 the short cross-bar 30 and the long cross-bar 31.

Figures 3 and 6 disclose the trip mechanism for these cross-bars which consists of a rod 32 disposed through the guide walls 29—29 and on which are the rockable arms 32, each provided 20 with an upstanding portion 34 provided with a beveled head 35.

Bell cranks 36—36 are also mounted on the guide walls 29—29 and each of these is provided with a beveled head 37. The adjacent ends of 25 the arms 33 are provided with reduced extensions 38 with which the lower portions of the bell cranks 36 engage and these ends of the bell cranks are connected to the reduced portions 38 of the arms 33 by springs 39 so that they are 30 inseparable.

The cross-bar 30 is secured to the belt 25 while the cross-bar 31 is free and is connected to the fixed cross-bar 30 by coiled extensible springs 40—40.

The connection of the block 30 to the belt 25 consists of spring members 41 extending from the cross-member 30 to the anchor 42 on the belt 25.

Rotatable posts 43—43 are provided on the 40 platform 9 and each carries a lamp 44 at its upper end. The lower ends of these posts are equipped with pulleys 45 which are connected to the shaft 17 by belts or endless cables 46.

Upon the top of the house-like structure 8 is 45 mounted a pivotal light or beacon 47.

It can now be seen, that a plurality of toy aeroplanes are mounted radially upon the turntable 11 and the crank 16 is turned. As the belt 25 rotates, the elongated cross-bar 31 will engage the pin 27 to one of the toy aeroplanes 28 and carry the same down until it is stopped by the head 35 of the trip mechanism. The belt continues on until the cross-member 30 strikes the edge of the triggers 36 whereupon the rocket 55

33 rock so that the heads 35 are lowered and as the springs 40-40 are now under tension, releasing of the cross-bars 31 will result in the forward snapping motion of the aeroplane as 5 it is carried by the cross-bar 31 with the result that the plane will rise from the platform and soar into the air.

While the foregoing specification sets forth the invention in specific terms, it is to be understood that numerous changes in the shape, size and materials may be resorted to without departing from the spirit and scope of the invention 10 as claimed hereinafter.

Having described the invention what is claimed 15 as new is:—

1. A catapult of the character described comprising an endless belt, a cross-member, spring means for connecting the cross-member to the belt, means for feeding aerial projectiles so that 20 they are engaged by the said cross-member, and means for tensioning the said cross-member and releasing the same at predetermined intervals of its travel.

2. A catapult of the character described comprising an endless belt, a cross-member, spring means for connecting the cross-member to the belt, means for feeding aerial projectiles so that they are engaged by the said cross-member, and 30 means for tensioning the said cross-member and releasing the same at predetermined intervals of its travel, said last-mentioned means consisting of a second block secured to the belt, a rockable member having a beveled head portion for stopping the first-mentioned cross member, and a trip for the said rockable member adapted to be operated by the second-mentioned cross-member.

3. A catapult of the character described com-

prising an endless belt, a cross-member, spring means for connecting the cross-member to the belt, means for feeding aerial projectiles so that they are engaged by the said cross-member, and means for tensioning the said cross-member and releasing the same at predetermined intervals of its travel, said last-mentioned means consisting of a second block secured to the belt, a rockable member having a beveled head portion for stopping the first-mentioned cross member, and a trip for the said rockable member adapted to be operated by the second-mentioned cross member, and a resilient connection between the last-mentioned cross-member and the belt. 5

4. A catapult of the character described comprising an endless belt, a cross-member, spring means for connecting the cross-member to the belt, means for feeding aerial projectiles so that they are engaged by the second cross-member, 10 and means for tensioning the said cross-member and releasing the same at predetermined intervals of its travel, said feed means consisting of a turntable and single operating means for rotating the turntable and actuating the said belt. 15

5. A catapult of the character described comprising an endless belt, a cross-member, spring means for connecting the cross-member to the belt, means for feeding aerial projectiles so that they are engaged by the second cross-member, 20 and means for tensioning the said cross-member and releasing the same at predetermined intervals of its travel, said feed means consisting of a turntable and single operating means for rotating the turntable and actuating the said belt, and a house-like structure having a doorway 30 therein, said house-like structure serving as a housing for the said turntable. 35

CHARLES DONALD FEIGHT.
